United States Patent Office

Des. 193,403
Patented Aug. 14, 1962

193,403

GLASS PANEL OR SIMILAR ARTICLE

Melvin Boldt, Chicago, Ill., assignor to Moffats Limited,
Weston, Ontario, Canada, a company of Ontario,
Canada

Filed Feb. 24, 1961, Ser. No. 64,050

Term of patent 14 years

(Cl. D36—11)

FIGURE 1 is a top plan view of a glass panel or similar article showing my new design;

FIGURE 2 is a side elevation view of the glass panel of FIGURE 1, and

FIGURE 3 is a greatly enlarged side elevation view of a portion of the glass panel of FIGURE 1 showing the design as being applied to the surface by means of etching.

I claim:

The ornamental design for a glass panel or similar article, as shown and described.
